ANTENNA AND LEAD-IN DEVICE

Hans Günter Engel, Berlin-Pankow, Germany,
assignor to Telefunken Gesellschaft für Draht-
lose Telegraphie, m. b. H., Berlin, Germany, a
corporation of Germany

Application May 26, 1933, Serial No. 672,979
In Germany May 28, 1932

4 Claims. (Cl. 250—33)

In modern broadcast receiver sets often antennæ of a few meters length are found sufficient to insure reception from local as well as from comparatively distant stations. As a result of the known distribution of stray fields in the interior of a building, indoor or room antennæ are not always serviceable. Now, the object of the invention hereinafter to be disclosed provides ways and means so that the necessary aerial is disposed in a simple manner outside the building, while the downlead brought to the receiver is accommodated inside a shielded flexible cable. While this idea has been basically known in the prior art, its application mostly proved impossible because of high cost of material and mounting as well as the lack of experts whose opinion could insure success with a shielded antenna arrangement only after an inspection of the locality and surrounding conditions.

20 A further object of the invention is to provide a simple and inexpensive antenna holder or support which may easily be attached to any desired part of a building, such as a window casement.

25 A still further object is to provide a simple arrangement whereby the lead in to the receiver is completely shielded between it and the antenna.

Other objects of the invention will be apparent to those skilled in the art as the description thereof proceeds. The preferred embodiment of the invention is disclosed in the attached drawing in which:

Fig. 1 shows the general arrangement of the antenna and the lead in to the receiver;

30 Fig. 2 shows the terminal connections for the receiver at the end of the lead in; and,

Figs. 3 and 4 show a front view and partial sectional view respectively of the antenna support and inner end of the antenna.

35 The new kind of antenna as here disclosed is fundamentally illustrated in Fig. 1, where *a* denotes the antenna properly so-called which has the form either of a metallic rod or of an insulation tube provided with an internal or external metallic conductor. The same is supported by a supporting means *b* which may be readily attached to the window frame *r* of wood or other insulation material. The construction may be chosen so that the aerial is firmly connected with the support or is shiftable thereon or removable therefrom. From the support *b* the screened cable *c* fixedly attached thereto is run down to the receiver apparatus *d*. The end thereof, as shown in Fig. 2, is fitted with two "banana" type 40 plug connectors, one of these plugs *s* being adapt-

ed to be joined with the antenna socket of the receiver set through the center conductor *u*, while the other *t* leads from the cable metallic shield *k* to the ground terminal of the set. Whether in addition a separate grounding of the 5 receiver is of advantage or whether the metallic cable shield could simply be used as a counterpoise is a point readily ascertainable by a practical test. As shown a metal ferrule *v* on the end of *k* is connected to plug *t* by a lead *w*.

10 The support *b* is separately shown again in Figs. 3 and 4 which illustrate the case where the antenna rod proper, which may be of a length ranging between 2 and 3 meters, is adapted to be removed from the holding or supporting means. 15 Figs. 3 and 4 show that the antenna rod need not be mounted absolutely vertically, but may be positioned also at an angle of inclination with reference to the support member.

20 Fig. 4 shows a sectional view of a support or aerial holder means. *e* denotes a metallic bush or sleeve in which is fixedly arranged an insulation tube *f*. Fitted in the latter is a metal piece *g* in the cavity of which is fitted the aerial *a*. By tightening the two screws *h* the antenna *a* can be 25 firmly and conductively connected with the metal sleeve *g*. Connected with the latter is the internal conductor *u* of the shielded cable *c*. The metal sheath *k* of the cable is united at the same time with the sleeve *e* as shown at 4.

30 It will then be seen that sleeve *e* and antenna holder *g* form supporting means for the end of cable *c*. As shown cylindrical sleeve *e* has an integral bracket or substantially flat end plate 5 formed therewith, one surface of which may be 35 in contact with window frame *r*, and supported thereby by screws, bolts or other well known fastening means, not shown. As shown, antenna *a* and members *e*, *f* and *g* have circular outlines or sections but other cross sectional shapes may 40 be used for these members, if desired.

The advantage of this antenna type is that the same may be mounted by inexperienced men. It may furthermore be disposed on a window or at some other place where interference need 45 to be feared not at all or only to a limited extent. The most favorable place is readily determinable empirically. In the case of network-supplied (all-electric) sets it is advisable to provide in addition some good arrester as found on the 50 market.

Where receiver sets are involved that are relatively insensitive whenever the antenna *a* is not long enough, an additional antenna wire *i* can be easily attached to the end of antenna *a* 55

as shown diagrammatically in Fig. 1, the said wire extension being either allowed to hang down or being brought to a supporting point in the neighborhood.

5. What may also be mentioned is that occasionally cases may arise where interference actions upon the antenna may arise at little distance outside the house. In a case like that a remedy and cure can be found in providing 10 a supplementary shielding piece extending, as it were, the sheath *e* of the supporter *b*.

While for purposes of description, a specific embodiment of my invention has been shown, it will be understood that it is not limited to 15 the form herein disclosed but is intended to include all structures coming within the scope of the following claims.

I claim as my invention:

1. In a device of the class described, the combination of a bracket having a substantially flat end portion adapted to be secured to a window frame, and an extending hollow sleeve portion, an insulating sleeve in engagement with the interior surface of said extending portion, a 25 metallic rod having an elongated hole therein supported within said insulating sleeve, said rod having a solid portion between the lower end of said hole and the outer surface of said bracket, an antenna consisting of a rigid metal 30 rod having an end portion extending within said elongated hole into contact with the solid portion of said rod and means engaging said insulating sleeve, said metallic rod and said antenna for retaining said antenna in a fixed position in said metallic rod.

2. In a device of the class described, a bracket formed of metal and having a hollow extending portion, an insulation sleeve mounted within said extending portion, a metallic rod mounted with-

in said sleeve and arranged to support an antenna, an antenna consisting of a thick rigid metal rod in engagement with said rod, a transmission cable having a center conductor connected to said metallic rod, and a metallic shield 5 enclosing said conductor having one end terminating in and in conductive connection with said bracket whereby the connection between the center conductor and the end of said antenna is shielded. 10

3. In a device of the class described, the combination of a metallic bracket having a flat end wall adapted to be clamped to a vertical wall and a hollow cylindrical sleeve extending upwardly at an acute angle to said end wall, said 15 sleeve being provided with an aperture, a hollow insulation sleeve mounted within said cylindrical sleeve, a metallic rod mounted within said insulation sleeve, said rod having a solid end portion at one end and a cylindrical bore extending 20 from its other end to said solid portion, a rigid, metallic rod constituting an antenna having one end seated in said cylindrical bore, the end of said antenna engaging the solid portion of said rod, and securing means passing through the 25 aperture in said cylindrical sleeve and engaging said antenna to secure it in position.

4. In combination, a bracket having a flat portion adapted to engage a vertical wall and a hollow portion extending upward at an acute 30 angle to said wall, a sleeve formed of insulation material secured within the hollow portion of said bracket, an antenna comprising a rigid metallic rod having its inner end mounted within and secured to said sleeve and a flexible wire 35 extension secured to and depending from the outer end of said rod.

HANS GÜNTER ENGEL.
